Primary Examiner—Carol Rademaker(74) *Attorney, Agent, or Firm*—Foley & Lardner LLP(57) **CLAIM**

I claim the ornamental design for a bottle, as shown.

DESCRIPTION

FIG. 1 is a top, front, right side perspective view of another embodiment of a bottle comprising the present invention.

FIG. 2 is a front elevational view thereof.

FIG. 3 is a rear elevational view thereof.

FIG. 4 is a right side elevational view thereof.

FIG. 5 is a left side elevational view thereof.

FIG. 6 is a top plan view thereof; and,

FIG. 7 is a bottom plan view thereof.

The broken lines shown in the drawing views are included for the purpose of showing environmental structure that forms no part of the claimed design.
